UNITED STATES PATENT OFFICE.

BARTON H. JENKS, OF BRIDESBURG, PENNSYLVANIA.

IMPROVEMENT IN RING-SPINNING FRAMES.

Specification forming part of Letters Patent No. 99,203, dated January 25, 1870.

To all whom it may concern:

Be it known that I, BARTON H. JENKS, of Bridesburg, in the county of Philadelphia and State of Pennsylvania, have invented certain new and useful Improvements in Ring-Spinning Machinery; and I do hereby declare that the following is a full, clear, and exact description thereof, reference being had to the accompanying drawings, making a part of this specification, in which—

Figure 1, Plate 1, is an elevation of one side of a ring-spinning frame having my improvements applied to it, showing the spindles upon which the cops are formed depressed. Fig. 2, Plate 2, is a transverse section taken through the oil-box, which incloses a part of the driving mechanism, in the vertical plane indicated by red line $x\ x$ in Fig. 1. Fig. 3, Plate 2, is a top view, in detail, of the heart-cam and the devices connected therewith for raising and depressing the spindle-carrying rails. Fig. 4, Plate 2, is an end view of the heart-cam, traveling tooth, vibrating tooth-carrying arm, and devices for adjusting the tooth automatically and by hand. Fig. 5, Plate 3, is a transverse section taken through Fig. 1 in the vertical plane indicated by line $z\ z$ thereon, looking toward the mechanism for moving the spindle-carrying rails. Figs. 6 and 7, Plate 3, show, in two positions, the heart-cam, which assists in communicating vertical movements to the spindle-carrying rails. Figs. 8 and 9, Plate 4, are diagrams intended to illustrate the movements which the spindles receive from the heart-cam during the operation of producing cylindrical cops terminated by cones at both of their ends.

Similar letters of reference indicate corresponding parts in the several figures.

The machine which I shall hereinafter describe is adapted for communicating a slow motion to the drawing-rolls by the employment of a worm-screw directly upon the shaft of the cylinder that drives the spindles, said worm-screw and its tangent-wheel, and the bearing or step of the shaft of this wheel, being arranged to work in a bath of oil, which will prevent undue friction upon said parts. By thus taking a slow motion directly from the shaft of the main cylinder, complication of spur-wheels of various sizes are obviated in obtaining the result stated.

The machine is also adapted for producing

cops, having their ends conical, with binding-threads constituting the layers in such conical ends, employing for this purpose a cam which is of a heart shape, and whose axis of motion is oblique to its highest and lowest points of throw, and using, in conjunction with such cam, a tooth which traverses longitudinally upon the surface of the cam as the latter slowly rotates, and which is applied to a vibrating arm that actuates the lifting-arms of the spindle-rails, as hereinafter explained.

In the machine which I shall describe a uniform distance is maintained between the traveler-rings and drawing-rolls during the operations of spinning and winding, and a given distance is maintained during said operations between the guide-wires and the rings or travelers, and also between the drawing-rolls and said wires, as will be hereinafter explained.

To enable others skilled in the art to understand my invention, I will describe its construction and operation.

In the accompanying drawings, Figs. 1 and 5, A represents the frame of the machine, which may be made for receiving spindles on both sides of it, and constructed in the usual well-known manner of constructing frames for ring-spinning machines. In the middle of the width of this frame A, and supported at its extremities in suitable journal-boxes on the ends of this frame, is the main shaft B, which is arranged in a horizontal plane, and provided with the drum C, which rotates the spindles a , through the medium of bands, in the usual well-known manner. One end of this drum-shaft B extends out from one end of the frame A, and is supported by a bearing-box upon a bracket or auxiliary frame, A'; and upon this extension of the shaft B are placed a worm-wheel, b , a driving-belt pulley, D, and a loose pulley, D'. The worm-wheel or screw b engages with the teeth of a tangent-wheel, b' , which is keyed upon a vertical shaft, E, and this worm-wheel, together with its tangent-wheel b' and the step-bearing of the shaft E, is arranged within an oil-box, E', as shown in Fig. 2. This box E' is supported in a suitable manner upon the frame A', and provided with a closely-fitting cover that consists of two hinged sections, E'', by raising which access can be had to the interior of the box. This box E' is designed for containing oil, so that

the wheels b b' and the step of said vertical shaft will be well lubricated. The upper part of the shaft E is sustained by a bracket secured to the frame A , and to the upper end of this shaft a bevel-pinion, c , is keyed, which engages with the teeth of a larger bevel-wheel, c' , on a horizontal transverse shaft, c^2 . This shaft c^2 is sustained by journal-boxes d d , and carries bevel spur-wheels c^2 near each end, which communicate rotary motion to the lowermost drawing-rollers e on both sides of the frame A . By means of spur-wheels on the drawing-rolls, as shown in Fig. 1, these rolls are caused to turn with a slow motion, and feed the roving or yarn to the spindles in a proper manner. These drawing-rolls may be constructed and supported in the usual well-known manner. The drawings show the said rolls and spindles only on one side of the frame A , and show the rolls mounted in inclined bearings upon the ends of short posts d d d' , which rise perpendicularly from a stationary horizontal rail, F . One end of the lowermost drawing-roll e carries a grooved belt-wheel, f , over which a belt passes that communicates rotary motion from said roller to a large belt-wheel, G , which is keyed upon a worm-shaft, G^2 , located in journal-boxes near the base of frame A , as clearly shown in Fig. 1. This worm-shaft operates the lift-motion of the spindle, a , as will be hereinafter explained.

The ring-rail J is applied to frame A in a horizontal position, and secured fast thereto by means of screws h h , which pass through oblong slots h' , made through the frame, and thus allow this ring-rail to be adjusted nearer to or farther from the rail F , and held in a position parallel to this latter rail.

Beneath the stationary but adjustable ring-rail J is the bolster-rail K , and beneath this bolster-rail and arranged parallel to it is the step-rail L , which latter rails are arranged parallel to the ring-rail, and are secured at a proper distance apart by means of posts j j . The rings K upon the rail J and their travelers, and also the spindles, their steps, and bolsters may all be constructed in the usual well-known manner. The ends of the two rails K L are notched and adapted for receiving feathers ll , applied in vertical positions upon the inner faces of the frame A , which feathers serve as guides for the said rails K L in their vertical motions. The two posts j j are extended down through the step-rail L , and are received by sockets in adjustable steps m m , which are pivoted to the free ends of vertically-vibrating lifting-arms g g' , which are keyed on the ends of horizontal rock-shafts H H' . These two shafts have their bearings in longitudinal supporting-bars I of frame A , and are connected together by means of vertical arms p p and connecting-rod p' , as shown in Fig. 1. To one of these shafts, H' , a loaded arm, p^2 , is secured, which is designed to assist in balancing the weight of the spindles and their rails, and also assist by its gravity to allow the descent of the said spindles and rails.

To the rock-shaft H two arms, S S , are rigidly applied, carrying on their free ends a horizontal transverse plate, S^2 , having a dovetail groove in its bottom surface, which receives and serves as a guide for a slide, S' . (Shown in dotted lines Fig. 3, and in the full lines in Figs. 4 and 5.) This slide carries upon an extended portion, t , a steel tooth, t' , which bears upon the surface of the heart-cam T , and is caused to move back and forth upon this cam in a direction with the length thereof, by means which will be hereinafter explained. The cam T is keyed upon a short shaft, n , which is caused to rotate slowly by the action of a worm-wheel, G' , upon a tangent wheel, G^2 , which latter is keyed to the cam-shaft n , as shown. This cam-shaft n is supported in bearings I-V, and is adjustable for setting the cam to work beneath the tooth t' to the best advantage. The slide S' receives through it a screw-rod, r , which has its bearing in one end of the vertically-vibrating plate S^2 , and which carries upon one end a ratchet-wheel, r' , and a bevel spur-wheel, r^2 . The teeth of the ratchet-wheel r' are engaged by a gravitating pawl, r^3 , which is pivoted to an arm, r^4 , extending from plate S^2 , and which will prevent the screw-rod r from turning backward. In Fig. 3 the pawl r^3 is thrown back, so as not to hide the ratchet. The spur-wheel r^2 engages with the teeth of a spur-wheel, b^4 , which is keyed on a hand-wheel shaft, b^5 , having its bearings on said arm r^4 , by means of which the tooth t' can be run back after a set of cops have been wound and set at any desired point upon its cam T for repeating the operation of winding. A vibrating pawl, W , which has its bearing upon the cam-shaft n , and which is loaded at one end, engages with the teeth on ratchet-wheel r' , and moves this wheel about its axis a distance equal to the space between each pair of teeth of said wheel once in every rotation of the cam-shaft n and cam T ; and thus the tooth t' will be caused to approach that end of the cam T giving the least upward throw by regular movements as this cam rotates and the work of winding progresses. The cam T is of the form of a true heart when taken at any point in cross-section, as shown in Figs. 7 and 8, and when taken longitudinally in the plane x x' its lines are parallel. This is shown clearly in the diagram, Fig. 9, wherein it will be seen that the shaft n , upon which this cam, is placed, passes obliquely through it, so that at one end the cam will give a greater upward throw than at the opposite end. The distance from x^2 to z at one end of the cam gives the greatest depression to each spindle, and the distance from z to x^2 at the same end of the cam gives the greatest upward throw to each spindle. Consequently the tooth t' should be at or near this end of the cam when the work of winding the cops is commenced, and the first and longest course of yarn is required upon each spindle. The distance between the points x and z at the opposite end of the cam gives the least depression to each spindle, and the

distance between the points $x' x^2$ gives the least upward throw to each spindle. Consequently as the tooth t' approaches this end of the cam the vertical movements of the spindles will be gradually shortened, which will in like proportion shorten the courses of thread wound upon each spindle, and produce a cop having a cylindrical body and tapering or conical ends, as indicated in Fig. 9. This Fig. 9 is intended to represent the movements which the cam T would give to a single spindle if supported directly upon it and moved along from the end $x^2 x'$ to the end $x' x^2$. As the cam revolves about its axis it will give a rapid descending movement to the spindle between the points $x' x^2$ on one side of the axis of the cam, and on equally rapid ascending movement to the spindle between the points $x' x^2$ on the opposite side of the axis. These rapid up and down movements take place when the yarn is being wound upon the lower end of the cop, and produce what is known as "binding-threads," for binding the several courses of yarn securely in place, so as to prevent the cop from casually unwinding when removed from its spindle. The same operation of winding binding-threads takes place at the upper end of each cop at the highest throws of the spindle.

I will now refer to the operation of the cam as arranged in Figs. 1, 3, 4, and 5. Motion being imparted to the shaft G^2 of the worm-screw G' from the pulley f on one of drawing-rolls e , this worm-screw operates upon the wheel G^2 on cam-shaft n , and communicates a slow rotary motion to cam T , which cam acts upon the traversing tooth t' , and gives vibrating movements to the plate S^2 and its arms $s s'$, which latter parts being applied to the shaft H will rock this shaft. By means of the two arms $p p'$, their connecting-rod p' , and the lifting-arms $g g'$ on shafts $H H'$, the rocking movements given to these two shafts will communicate vertical reciprocating movements to the spindle-rails and their spindles, which latter movements will vary in length according to the varying throws of the heart-cam. At the commencement of the operation the tooth t' is adjusted near that end of the cam T which gives the greatest throw, by turning the hand-wheel shaft b^2 , and at every rotation of the cam T the pawl W will move the tooth t' nearer to that end of this cam which gives the least throw. As the tooth t' approaches that end of the cam which gives the least throw, the rising and descending strokes of the spindles a will be gradually shortened, thereby winding the yarn upon the spindles in the form above stated. When the spindles have been filled and the cops removed from them, the tooth t' is run back by turning the hand-wheel shaft b^2 so as to rest upon that end of the heart-cam which gives the greatest upward throw, to repeat the operation of winding.

For the purpose of keeping the strand of

yarn centrally over their respective spindles a , I employ eye-pieces $P P'$, which may be made in any suitable manner. Those represented in the drawings are simply short pieces of wire with their extremities coiled in the form of eyes, the centers of which coincide with the vertical axes of their respective spindles. The eyes P guide the strands of yarn on their way from the drawing-rollers $e e e$ to the travelers, and it is important to have said eye-pieces maintain a uniform distance from the ring-rail, so that the angle of the thread and the resistance of the air upon it will always be uniform, whatever may be the positions of the other parts of the spinning and winding devices. Where the ring-rail J is stationary, this may be done by securing the guide-wires P to the bar F , which supports the drawing-rollers; but in spinning-frames where the ring-rail is movable and the spindle-rails are stationary, the guide-wires P may be secured to the ring-rail, or, if desirable, the guide-wires may be applied to the stationary ring-rail shown in the drawings.

While I prefer to have the spindle-supports vertically movable, and the ring-rail J stationary, I do not confine my cam motion to this arrangement, as this motion can be applied with beneficial results to operate a movable ring-rail which is used with spindles whose bearings are stationary.

Having described my invention, what I claim as new, and desire to secure by Letters Patent, is—

1. A horizontally-traversing tooth, t' , applied to a vertically-vibrating plate, S^2 , in combination with a rotating heart-cam, T , constructed so as to communicate such movements to the spindles as will produce cops of the specified form, substantially as described.
2. The combination, with the heart-cam T and a vibrating plate, S^2 , which carries the tooth t' , of a pawl, W , and a ratchet-wheel, r' , the former being pivoted to the cam-shaft n , and the latter being keyed to the screw-shaft r , so that at every upward movement of said plate S^2 the tooth t' will be moved a given distance in a direction with the length of the heart-cam T , substantially as described.
3. A heart-cam constructed as set forth, and applied fast to a short rotary shaft, n , which is arranged at right angles to the length of the bars I , in combination with a tooth, t' , which receives vertically-vibrating movements substantially as and for the purposes set forth.
4. The horizontal transverse rock-shafts $H H'$, carrying the lifting-arms $g g'$ and arms $p p'$, the latter being connected by a rod, p' , in combination with a vertically-vibrating plate, S^2 , traversing tooth t' , and a heart-cam, T , all constructed, arranged, and operating substantially as described.
5. The spur-wheel r^2 on screw-shaft r , and the spur-wheel b^2 on a hand-wheel shaft, b^2 , in combination with a vibrating tooth-carrying plate, S^2 , and with a heart-cam, construct-

ed and arranged to operate substantially as described.

6. A vertically-adjustable ring-rail, J, in combination with vertically-reciprocating rails K, L and adjustable steps m, applied to the arms g, substantially as described.

7. The worm b on the end of the spindle

driving shaft, the pinion b', the shaft E, and the covered oil-box E', all arranged substantially as and for the purpose described.

BARTON H. JENKS.
